Specification of Letters Patent. Patented July 13, 1915.

Application filed July 15, 1912. Serial No. 709,430.

To all whom it may concern:

Be it known that I, MORTON L. JOHNSON, citizen of the United States, residing at Chicago, in the county of Cook and State of Illinois, have invented a certain new and useful Improvement in Telephone Exchange Systems, of which the following is a full, clear, concise, and exact description, reference being had to the accompanying drawings, forming a part of this specification.

My invention relates to telephone exchange systems and has for its general object the provision of operator controlled electro-magnetic switching mechanism for extending calling lines into connections with operator selected link connectors and the extension of the link connectors into connection with additional link connectors further taking part in establishing connection between calling and called lines.

In practising my invention a receiving operator operates a link selector switch to bring the first link connector into connection with the switch of such selector and thereafter operates the electro-magnetic mechanism of a second switch to connect the first link connector with the second link connector.

In one embodiment of the invention, to which embodiment the invention is not to be limited, the second switch is individual to the second link connector and the second link connector is individual to the switch of an ordinary connector switch such as is employed in automatic telephone practice whereby the final step in the operation of connecting calling and called lines may also be effected by the operator who has thus extended a calling line.

The system described is one which may include nine hundred lines. If the system has more lines there would be additional link connectors and additional operator controlled selector switches for including them in the telephone circuit to be established.

I will explain my invention more fully by reference to the accompanying drawings showing the preferred embodiment thereof and in which—

Figure 1 is a view generally outlining the equipment which I employ and Figs. 2, 3 and 4, taken collectively and in numerical order, represent the system in more of its

details, the equipment illustrated being adapted to a nine hundred line system in which an operator receiving a call may establish the entire connection between calling and called subscribers, though the invention is not to be limited to the number of lines employed nor to the establishment of the final connection by the operator between the called line and the final link connector selected by the receiving operator and brought into connection with a calling line.

Referring first particularly to Fig. 1, I have there shown (in the case of a nine hundred line system) a subscriber's station 111 in the first group of one hundred lines and another subscriber's station 201 in the second group of one hundred lines, the lines being divided into nine groups of one hundred lines each, the first line in the first group being numbered 100.

When a calling subscriber (say at station 111) initiates a call the telephone equipment 1 at some idle operator's position is selected by an operator selector switch 2 which is set into operation by the equipment of a calling line and which is arrested when waiting contacts peculiar to an idle operator are encountered by the traveling wipers of the idle operator selector switch. Each operator selector switch 2 includes equipment, generally illustrated in Fig. 1, but more fully illustrated in the remaining figures, by which the switching apparatus 3 belonging to the selected idle operator is extended into connection with an operator controlled link connector switch 4. The wipers of the selector switches 4 are shown as being individual to the subscribers' lines, though the invention is not to be thus restricted. Each selector switch 4, in the system described, may be provided with nine sets of waiting contacts, one contact of each such set being illustrated in Fig. 1. Each such set of contacts is multiply related with and is individual to two sets, and only two sets, of waiting contacts each in a second link selector 5. Each first link selector switch 4 thus is related to certain waiting contacts of eighteen second link selector switches 5, there being two switches 5 for each set of contacts belonging to each switch 4, these two switches 5 being, as a pair, related (by means of its one hundred sets of waiting contacts) with one hundred

switches 4, each set of waiting contacts of each switch 5 being individual to one switch 4.

In the system assumed there are one hundred sixty-two switches 5 for the nine hundred lines and as each switch 5 is individual to a connector switch 6 there are one hundred sixty-two such connector switches, each accessible to each of the lines of the 10 group of one hundred to which such selector switches are apportioned. As illustrated, each pair of switches 5 is accessible only to the lines of the associate group of one hundred lines that has the switches 4, 15 while the pair of associated connector switches 6 is also limited to such association with calling lines in the group of one hundred lines to which the switches 5 and 6 are apportioned, though the invention is obviously not to be restricted to such an embodiment. The set of wipers of each selector switch 5 is individual to a set of wipers of the associate connector switch 6 which 20 may be of the usual type employed in automatic telephone exchange practice when the operator is to complete the entire connection. While the waiting contacts of each pair of switches 5 are individual to a group of one hundred lines each group of one hundred 25 lines has apportioned thereto the wipers of nine pairs of switches 5 and their waiting contacts, each pair of such wipers being individual to a group of one hundred lines. In this way any of the nine hundred lines, 30 when a calling line, may have access to some switch 5 whose wipers are individual to the group of one hundred lines that includes the line desired by the calling line. British Patent 1298 of 1910 may be referred to as 35 illustrating the general operation of connector switches such as are indicated at 6. Van Deventer's "Telephonology," page 530, illustrates the mechanism which may be employed in the connector switches and some of 40 this mechanism is employed in the construction of switches 4 and 5.

If the desired line is in the first group of one hundred the operator steps the wipers of switch 4 which she employs into engagement with the first set of waiting contacts. 50 If the desired line is in the second group of one hundred these wipers are brought into connection with the second set of waiting contacts, and so on, there being, as is now understood, nine sets of these waiting contacts for each switch 4, each set of contacts being peculiar to link connectors 7 that in turn are each individual to a pair of switches 5. The operator having arbitrarily 55 stepped the wipers of the first link selector 4 into connection with a link 7 pertaining to the switches 5 and 6 belonging to the group of one hundred lines in which the desired line is included, automatically effects the operation of the first of the two switches 5 that

is in order (one switch 5 being operated before the other switch 5 can be operated if both switches 5 are idle at the time of the employment of one of them), or the remaining of these two switches if one of them is 75 busy, whereby the arbitrarily selected link 7 is automatically connected with the switch 5 and is thereby automatically extended into connection with connector switch 6 associated therewith that is to be employed in 75 further extending or finally completing the connection. After a switch 5, say the upper switch in Fig. 1, has been thus automatically brought into connection with the operator selected link 7, the contacts of the remaining 80 switch 5 in multiple with the contacts of the first switch 5 that establish the connection between the connector switch 6 and the employed link 7 is made busy so that the second switch, when set into operation to extend another calling line in the same group with line 111, will not stop upon such contacts thus made busy but will pass on into engagement with the contacts of the newly 85 operated selected link 7, an additional line 90 112 being illustrated with a first link selector switch 4 in association with the two second link selector switches 5 belonging to the switches 4 of the first group of one hundred lines. Thus the lines of a group are adapted 95 to have access to the first switch 5 in order, if both of these switches are idle and is adapted to have access to the idle one of these two switches 5 if the other is busy, it being estimated that eighteen switches 5 in 100 the nine hundred line system illustrated will be sufficient for each group of one hundred such lines, each of the nine sets of waiting contacts of the first link selectors 4 belonging to the first group of one hundred lines 105 having the waiting contacts of two switches 5 individual thereto as has been described, the first waiting contacts of one switch 4 being connected with the first waiting contacts of two switches 5 belonging to the 110 group of first one hundred lines, the first contacts of the next switch 4 of the same group being connected with the next contacts of these two switches 5, the first contacts of the third switch 4 (not shown) of 115 the same group being connected with the next contacts of these two switches 5, and so on, there thus being one hundred sets of waiting contacts for each switch 5 where each line has a first link selector 4 individual thereto.

The second contacts of each switch 4 in a group are similarly related to the pair of second link selectors 5 pertaining to the second group of one hundred lines, the third 120 contacts of each switch 4 in a group are similarly related to the pair of second link selectors 5 pertaining to the third group of one hundred lines, and so on, the final contacts of the switches 4, as the invention is 125 130

illustrated, being similarly associated with the pair of second link selector switches 5 that pertain to the ninth and last group of one hundred lines. The selected operator, by means of the device 3, has thus arbitrarily appropriated the link 7 that extends to waiting contacts of the switches 5 belonging to the group of one hundred lines in which the desired line is included. Assuming that station 111 desired communication with station 112, the operator will manipulate the device 3 to bring the wipers of the first link selector 4 of the calling line into connection with the first set of waiting contacts pertaining to the single link selector 7 individual to the employed selector 4 and having waiting contacts in the switches 5 that pertain to the first group of one hundred lines. The selected one of the two switches 5 is set into operation to cause its wipers to stop upon the waiting contacts pertaining to the operator selected link 7 thereby to associate the link connectors 6 individual to the employed switch 5 with the employed link 7. The connector switch 6 shown being of the type employed in automatic practice, the operator manipulates the same device 3 and causes the wipers of the connector switch 6 to be stepped up to the level of that bank of waiting contacts corresponding to the tens in which waiting contacts of the desired line are included whereafter the same device 3 serves to step the wipers of the employed connector switch 6 around until these wipers encounter the waiting contacts of the desired line, the usual busy test being conveyed if the desired line is busy and the usual signaling circuit being established if the desired line is free. As the invention is practised, two of the wipers of the employed link selector switch 4 are connected with a calling line and thus constitute calling line extensions and in a measure may be said to constitute links in the connection between calling and called lines. I have shown no selector switches for bringing these wipers into connection with calling lines and have therefore called the switches 4 the first link connector switches but I do not intend thereby to limit myself to the non-employment of preceding selector switches, and while the switches 4 are shown as being electro-magnetically operated, I do not wish to be limited to this feature for enabling the operator arbitrarily to select link connectors 7. I term the switches 4 the first link selector switches as they are here shown as being the first to be operated and which the operator employs in arbitrarily appropriating link connectors 7. I term the switches 5 second link selector switches as they are the second switches to operate automatically to become connected with operator appropriated links 7.

The invention will now be further explained in connection with Figs. 2, 3 and 4 in which I have illustrated the equipment associated with two lines (111 and 112) in the same group of one hundred lines. Each telephone station illustrated includes a telephone switch hook 8 having a normal contact serving, when the telephone receiver 9 is upon the switch hook, to establish a bridge connection between the line sides that includes a signal bell 10 and condenser 11. The switch hook has an alternate contact serving when the telephone receiver is removed therefrom to complete a metallic bridge connection between the line sides that includes the telephone receiver 9 and the telephone transmitter 12. Each line terminates at the exchange in the armature switches of a cut off relay 13 whose normal contacts are connected with the intermediate armature switches of a switching relay 14, the normal contacts of these latter armature switches being connected with the upper and lower windings of a line relay 15, the lower winding being directly grounded while the upper winding is grounded through the common battery 16. The line relay 15 is thus included in a closed circuit when the telephone receiver at a calling station is removed from its switch hook.

When the relay 15 is energized a circuit is established which may be traced from its upper grounded armature switch, the alternate contact of such armature switch, the sluggishly operating interrupter relay 17, the rotary magnet 18, the side switch wiper 19 in its first position, to the grounded common battery 16. The rotary magnet 18 now sets the wipers 20, 21, 22, 23, 24 and 25 into step by step movement until the wiper 22 encounters an ungrounded waiting contact whereupon all of these wipers are stopped, since the circuit for the private magnet 26 (which circuit was established upon the initial operation of the rotary magnet 18) is opened at the wiper 22, said private magnet then causing the side switch wipers 19 and 27 to step to their second positions. When the side switch wiper 19 steps into its second position circuit for the rotary magnet 18 is opened. When the side switch wiper 27 is stepped into its second position the associate wiper 22 is grounded so that the contact engaged by this wiper 22 is grounded whereby other operator selector switches 2 having contacts in multiple with waiting contacts of the wipers 22 will not permit their wipers 22 to rest upon those waiting contacts that are in multiple with the contacts thus grounded through the side switch wiper 27 of an employed operator selector switch. The other wipers of the operator selector switches are provided with waiting contacts, the contacts of each set of each switch

being multiply related with similar contacts of other switches. The operator's telephone 1 has telephone conductors provided with multiply related contacts provided for the 5 wipers 20 in the different operator selector switches and multiply related contacts provided for the wipers 21 in the different operator selector switches, whereby the wipers 20 and 21 that are brought to rest connect 10 some operator's telephone set 1 with the calling line. The calling subscriber tells the operator the number of the desired line and the operator thereafter manipulates a suitable circuit interrupter device, simply shown 15 as a key 3, for interrupting the circuit of the line relay 28, the circuit for this relay having been previously established due to a circuit from the grounded battery 16, the side switch wiper 19 in its second position, 20 the relay 29, the lowermost armature switch of relay 15, to ground, the upper armature switch of the now energized relay 29 establishing a circuit which may be traced from the upper grounded winding of relay 25 28, the upper armature switch of relay 30 and its normal contact, the upper armature switch of relay 29 and its then engaged contact, the wiper 23 and its engaged contact the circuit interrupting 30 device 3, the wiper 24 and its then engaged contact, the intermediate armature of relay 29, the intermediate armature switch of relay 30, the lower coil of relay 28, to the grounded battery 16. The relay 28 is, by 35 means of the device 3, operator controlled and whenever the device 3 is actuated the circuit for the relay 28 is broken whereupon the lower armature of the relay 28 engages its normal contact to establish a circuit from 40 this lower armature, which is grounded, the normal contact of such armature, the armature switch of sluggishly operating relay 31 (whose circuit was previously established when the relay 28 was energized, as will be 45 apparent) the alternate contact of this latter armature switch, the sluggishly operating relay 32, the rotary magnet 33, the common battery 16, to ground. The rotary magnet 33 is thus operated as often as the operator 50 desires to cause the arbitrary movement of the wipers 34, 35, 36 and 37 into connection with the link connector (indicated at 7 in Fig. 1) which the operator has appropriated for use and which link connector is 55 of such relationship as to enable it to be employed for uniting the desired line with the calling line. The waiting contacts engaged by the wipers 34, 35, 36 and 37 are provided with conductors 7¹, 7², 7³, 7⁴ that 60 extend therefrom to equipment that pertains to the link selector switches 5, conductors 7¹, 7², and 7⁴ extending directly to waiting contacts provided for the wipers 38, 39 and 40, while the conductor 7³ extends 65 to electro-magnets 41 whose armature

switches are grounded upon the associate waiting contacts of wipers 42 of the different switches 5.

When the wiper 36 engages a conductor 7³ pertaining to the link connector arbitrarily selected by the operator, a circuit is established which is traced from the grounded upper armature switch of relay 28 and its then engaged contact, the upper armature switch of relay 32 and its then engaged contact (this armature switch being free of its contact during the time that the wipers 34 to 37 are being stepped around owing to the sluggishness of the relay 32) the wiper 36, the selected conductor 7³, the relay 41, the grounded battery 16, to ground. The armature switch of relay 41 then engages its alternate contact and establishes a circuit which may be traced from the grounded armature switch of relay 41, its alternate contact, the upper armature switch of relay 43 and its normal contact, the upper intermediate armature switch of relay 44 and its normal contact, the winding of sluggishly operating relay 45, the common battery 16, to ground. The intermediate armature switch of relay 45 then establishes a circuit which may be traced from this armature switch which is grounded, the alternate contact of this armature switch, the rotary magnet 46, the sluggishly operating relay 47, the armature of this relay and its contact, the side switch wiper 48, the grounded battery 16, to ground. The rotary magnet 46 thereupon causes the wipers 38, 39, 40 and 42 to rotate until the wiper 42 engages a contact from which ground has been removed by the associate magnet 41 in bringing its armature from its normal to its alternate contact. When the wiper 42 thus encounters a contact from which ground is thus removed the circuit for the private magnet 49 (which was initially established upon the first operation of the rotary magnet 46) is opened whereby the side switch 105 wipers 48, 50 and 50¹ are moved from their first positions to their second positions. It may be said that the circuit initially established for the private magnet 49 by the rotary magnet 46 may be traced from the 110 grounded armature switch of relay 46 and its then engaged contact, the winding of magnet 49, the side switch wiper 48 in its first position, the battery 16, to ground and that the circuit secondarily established for 115 the private magnet 49 may be traced from the grounded armature switch of the associate relay 41 and its normal contact, the wiper 42, the lower armature switch of relay 43, the side switch wiper 50 in its first position, the magnet 49, the side switch wiper 48 in its first position, the battery 16, to ground. The wiper 48, in being moved to its 120 second position, opens circuit for the rotary magnet 46 so that the wipers 38, 39, 40 and 125 130

42 are arrested. The side switch wiper 48 in its second position also closes a circuit for the relay 44 which may be traced from the grounded battery 16, the side switch wiper 48 in its second position, the relay 44, the lower armature switch of relay 45, to ground. When the relay 44 is energized its top and bottom armature switches are attracted to connect the top wiper 38 and the bottom wiper 40 with the side switch wipers 51 and 52 of the associate connector switch 6, the two upper switches of relay 30 now being attracted to connect the key 3 with the wipers 34 and 37, the circuit for the magnet 30 being traceable from the grounded battery 16, the side switch wiper 52¹ in its second position, the relay 30, the wiper 35, the conductor 7², the wiper 39, the side switch wiper 50¹, to the then grounded upper armature switch of relay 68. The side switch wiper 52¹ is brought into second position by the private magnet 52² whose circuit was maintained during the impulses, occasioned at 3, by the sluggishly operating relay 32. When the series of impulses is ended the magnet 52² is deenergized and the side switch wiper 52¹ is placed in second position. A relay 53 is in metallic bridge of the conductors extending to the wipers 51 and 52 and circuit therefor is completed by way of the key 3 at the selected operator's position. The operator by means of the key 3, may interrupt the circuit of the relay 53 and cause the operation of the connector switch in a manner well known, it being sufficient, to enable those skilled in the art to understand the illustration, to name the parts of the connector switch diagrammatically illustrated. The connector switch shown includes a vertical magnet 54, rotary magnet 55, ringing magnet 56, release magnet 57, off normal switch 58, ringing generator 59, private relay 60, private control relay 61, side switch wipers 51, 52, 62 and 63, armatures 64, 65 of the ringing relay 56, ringing cut-off relay 66, back bridge relay 67, release control relay 68, impulse control relay 69, busy tone device 70, and the wipers 71, 72 and 73, the wipers 71 and 73 being included in the telephone circuit when established between the calling and called lines.

When the switching relay 44 of the switch 5 was brought into operation circuit of relay 45 was opened and the ground established at the lowermost armature switch of this relay 45 was removed but is replaced at the upper armature switch of relay 68, relay 45 being sufficiently sluggish in action to permit ground to be established at the upper armature switch of relay 68 before it is removed at the lower armature switch of relay 45. Thus the relay 44 of switch 5 is maintained energized until there is no metallic bridge between the talking sides of the circuit between calling and called sta-

tions so that when the telephone receivers at both of these stations are upon their hooks the circuit for the magnet 44 is broken at the upper armature switch of relay 68, the circuit of relay 68 being dependent upon the relays 53 and 67 as will be well understood by those skilled in the art. When the waiting contacts of the desired line have been engaged the operator manipulates her key 74 to establish a circuit which may be traced from the grounded battery 16, the contacts of the key 74, the wiper 25, the lowermost armature switch of relay 29, the winding of relay 14, the wiper 35, the conductor 7², the wiper 39, wiper 50¹ in its second position, to the upper armature switch of relay 68 which is then grounded. The relay 14 is thereby energized to bring its intermediate armature switches into engagement with their alternate contacts whereby the calling line is brought into direct connection with the employed switch 4 and the operator's telephone equipment 1 is cut out of circuit. The operator's telephone set is cut out owing to the deenergization of relay 15 which causes the release magnet 75 to be included in a circuit that includes the grounded battery 16, the previously established off normal contact 76, said magnet 75, the uppermost grounded armature switch of relay 15 and its normal contact. All of the wipers of the operator selector switch 2 are now restored to normal and the operator's telephone outfit is cut out of circuit. When the relay 14 was energized it established a locking circuit through itself which is traced from the grounded battery 16, the lowermost armature switch of relay 14 and its then engaged contact, the winding of relay 14, the wiper 35, the conductor 7², the wiper 39, the wiper 50¹ in its second position, the upper armature switch of relay 68 to ground. When the relay 68 is deenergized in the manner which has been described this locking circuit is broken so that the calling line equipment is restored to normal. When the relay 68 of the connector switch is deenergized (which can only occur when the receivers at the calling and desired stations are upon their switch hooks) the connector switch is restored to normal in a manner well known and the wipers of switches 4 and 5 are restored to normal owing to the deenergization of relays 44 and 30. When relay 44 is deenergized the circuit for the release magnet 43 is closed from the grounded battery 16, the previously closed off normal switch 77, the release magnet 43, the lower intermediate armature switch of relay 44, the intermediate armature switch of relay 45, to ground. The magnet 43 thereupon causes the side switch wipers 48, 50 and 50¹ and the wipers 38, 39, 40 and 42 to be restored to normal. When relay 30 is deenergized cir-

cuit is established for release magnet 78 which may be traced from the grounded battery 16 through the previously closed off normal switch 79, the release magnet 78, 5 the lowermost armature switch of relay 30, the armature switch of relay 31, and its normal contact, the lower armature switch of relay 28 and its normal contact, to ground. The release magnet 78 thereupon restores 10 the side switch wiper 52¹ and the wipers 34, 35, 36 and 37 to normal, and as circuit for relay 14 is broken at the upper armature switch of relay 68 the entire equipment is restored to normal.

15 I have described a connection which initiates from the station 111. The equipment illustrated in connection with station 112 is similar to that illustrated in connection with station 111 and similar parts are given 20 similar characters of reference. The two switches 5 illustrated in Fig. 3 pertain to the first group of one hundred lines and, if both switches are idle, one of these switches is subject to employment before the other.

25 If one of these switches is busy the other switch is then alone subject to employment by a new calling subscriber in the particular group of one hundred lines. In order that one switch 5 may be employed in advance of 30 another when both switches are idle I make the alternate contacts of the relay 41 of the switches 4 of each group of one hundred lines common to the lead 80 which goes to the first switch 5 and there terminates at the 35 upper armature of release magnet 43. When this armature is in normal position and when the upper intermediate armature switch of relay 44 is in normal position the selector switch 5 which has these armatures that are thus connected with alternate contacts of relays 41 is first subject to operation. When the first switch 5 is employed the upper intermediate armature switch of 40 relay 44 engages its alternate contact whereby circuit is established which may be traced from the grounded battery 16, the relay 45 of the lower switch 5, the normal contact of the upper intermediate armature switch of relay 44 of the lower switch 5, and said 45 armature switch, the normal contact of the upper armature switch of relay 43 of the lower switch 5, the upper armature switch of relay 45 of the upper switch 5, the alternate contact of the upper intermediate armature switch of relay 44 of the upper switch 5, and the normal contact of the upper switch of the relay 43 of the upper switch 5, the lead 80, to the attracted ground- 50 ed armature switch of relay 41 employed by the second seeking line in the group of one hundred. When any switch 5 is in use it is guarded against further appropriation by the ground established by the armature switch of relay 41 and the normal contact, 55 the circuit of relay 41 being opened when the

relay 30 is energized to open the circuit of relay 28.

Cross reference is made to my co-pending application Serial No. 709,422, filed July 15, 1912, wherein I have disclosed a telephone exchange system including a plurality of subscribers' lines, a plurality of primary intercommunicating links between subscribers' lines converging upon a central point, and normally disconnected from each other, automatically operating connecting means and control devices at the central point for effecting connections of said links to each other and over said links in opposite directions from the central point to subscribers' lines. Features not herein claimed are claimed in the said co-pending application.

While I have herein shown and particularly described my invention, I do not wish to be limited to the precise details of construction and circuit arrangement illustrated as changes may readily be made without departing from the spirit thereof.

Having thus described my invention, I claim as new and desire to secure by Letters Patent the following:

1. A telephone exchange system including telephone lines extending from stations to an exchange; link connectors at the exchange for extending calling lines; operator controlled switching apparatus for joining operator controlled link connectors with calling lines; additional link connectors; electro-magnetically operated selector switches for joining the additional link connectors with the aforesaid link connectors; operator controlled means for setting the selector switches into automatic operation; operator controlled means for manually governing the extent of automatic operation of said selector switches; and operator controlled electro-magnetically operated connector switches for connecting the selector switches that are connected with operator appropriated link connectors, with desired lines.

2. A telephone exchange system including telephone lines extending from stations to an exchange; link connectors at the exchange for extending calling lines; operator controlled switching apparatus for joining operator selected link connectors with calling lines; additional link connectors; electro-magnetically operated selector switches for joining the additional link connectors with the aforesaid link connectors; automatically operating operator controlled means for governing the operation of said selector switches and causing them to become automatically connected with the first aforesaid link connectors when they are taken for use; and operator controlled electro-magnetically operated connector switches for connecting the selector switches that are connected with operator appropriated link connectors, with desired lines.

3. A telephone exchange system including telephone lines extending from stations to an exchange; link connectors at the exchange for extending calling lines; operator controlled switching apparatus for joining operator selected link connectors with calling lines; additional link connectors; electro-magnetically operated link selector switches for joining the additional link connectors with the aforesaid link connectors; means governed by said operator controlling switching apparatus and operating over operator selected link connectors for governing the operation of said selector switches to cause them to remain in connection with operator selected link connectors; and operator controlled electro-magnetically operated connector switches for connecting the selector switches that are connected with operator appropriated link connectors, with desired lines. 65

4. A telephone exchange system including telephone lines extending from stations to an exchange; link connectors at the exchange for extending calling lines; operator controlling switching apparatus for joining operator controlled link connectors with calling lines; additional link connectors; electro-magnetically operated selector switches for joining the additional link connectors with the aforesaid link connectors; operator controlling means for governing the operation of said selector switches; means for preventing selector switches from remaining in connection with operator appropriated link connectors that are in connection with other selector switches; and operator controlled electro-magnetically operated connector switches for connecting the selector switches that are connected with operator appropriated link connectors, with desired lines. 70

5. A telephone exchange system including telephone lines extending from stations to an exchange; link connectors at the exchange for extending calling lines; operator controlled switching apparatus for joining operator selected link connectors with calling lines; additional link connectors; electro-magnetically operated selector switches for joining the additional link connectors with the aforesaid link connectors; automatically operating operator controlled means for governing the operation of said selector switches and causing them to become automatically connected with the first aforesaid link connectors when they are taken for use; means for preventing selector switches from remaining in connection with operator appropriated link connectors that are in connection with other selector switches; and operator controlled electro-magnetically operated connector switches for connecting the selector switches that are con- 75

nected with operator appropriated link connectors, with desired lines. 65

6. A telephone exchange system including telephone lines extending from stations to an exchange; link connectors at the exchange for extending calling lines; operator controlled switching apparatus for joining operator selected link connectors with calling lines; additional link connectors; electro-magnetically operated link selector switches for joining the additional link connectors with the aforesaid link connectors; means governed by said operator controlled switching apparatus and operating over operator selected link connectors for governing the operation of said selector switches to cause them to remain in connection with operator selected link connectors; means for preventing selector switches from remaining in connection with operator appropriated link connectors that are in connection with other selector switches; and operator controlled electro-magnetically operated connector switches for connecting the selector switches that are connected with operator appropriated link connectors, with desired lines. 75

7. A telephone exchange system including telephone lines extending from stations to an exchange; link connectors at the exchange for extending calling lines; operator controlling switching apparatus for joining operator controlled link connectors with calling lines; additional link connectors; electro-magnetically operated selector switches for joining the additional link connectors with the aforesaid link connectors; operator controlled means for governing the automatic operation of said selector switches; operators' responsive devices at different operators' positions; and selecting mechanism for selecting operators' responsive devices that are free for selection, the link connectors performing their line joining functions independently of said selecting mechanism that selects operators' responsive devices. 90

8. A telephone exchange system including telephone lines extending from stations to an exchange; link connectors at the exchange for extending calling lines; operator controlled switching apparatus for joining operator selected link connectors with calling lines; additional link connectors; electro-magnetically operated selector switches for joining the additional link connectors with the aforesaid link connectors; automatically operating operator controlled means for governing the operation of said selector switches and causing them to become automatically connected with the first aforesaid link connectors when they are taken for use; operators' responsive devices at different operators' positions; and selecting mechanism for selecting operators' responsive devices that are free for selection, 105

the link connectors performing their line joining function independently of said selecting mechanism that selects operators' responsive devices.

- 5 9. A telephone exchange system including telephone lines extending from stations to an exchange; link connectors at the exchange for extending calling lines; operator controlled switching apparatus for joining operator selected link connectors with calling lines; additional link connectors; electro-magnetically operated link selector switches for joining the additional link connectors with the aforesaid link connectors; means governed by said operator controlled switching apparatus and operating over operator selected link connectors for governing the operation of said selector switches to cause them to remain in connection with operator selected link connectors; operators' responsive devices at different operators' positions; and selecting mechanism for selecting operators' responsive devices that are free for selection, the link connectors performing their line joining function independently of said selecting mechanism that selects operators' responsive devices.

- 10 10. A telephone exchange system including telephone lines extending from stations to an exchange; link connectors at the exchange for extending calling lines; operator controlled switching apparatus for joining operator controlled link connectors with calling lines; additional link connectors; electro-magnetically operated selector switches for joining the additional link connectors with the aforesaid link connectors; operator controlled means for governing the operation of said selector switches; means for preventing selector switches from remaining in connection with operator appropriated link connectors that are in connection with other selector switches; operators' responsive devices at different operators' positions; and selecting mechanism for selecting operators' responsive devices that are free for selection, the link connectors performing their line joining function independently of said selecting mechanism that selects operators' responsive devices.

- 15 11. A telephone exchange system including telephone lines extending from stations to an exchange; link connectors at the exchange for extending calling lines; operator controlled switching apparatus for joining operator selected link connectors with calling lines; additional link connectors; electro-magnetically operated selector switches for joining the additional link connectors with the aforesaid link connectors; automatically operating operator controlled means for governing the operation of said selector switches and causing them to become automatically connected with the first aforesaid link connectors when they are

taken for use; means for preventing selector switches from remaining in connection with operator appropriated link connectors that are in connection with other selector switches; operators' responsive devices at different operators' positions; and selecting mechanism for selecting operators' responsive devices that are free for selection, the link connectors performing their line joining function independently of said selecting mechanism that selects operators' responsive devices.

- 20 12. A telephone exchange system including telephone lines extending from stations to an exchange; link connectors at the exchange for extending calling lines; operator controlled switching apparatus for joining operator selected link connectors with calling lines; additional link connectors; electro-magnetically operated link selector switches for joining the additional link connectors with the aforesaid link connectors; means governed by said operator controlled switching apparatus and operating over operator selected link connectors for governing the operation of said selector switches to cause them to remain in connection with operator selected link connectors; means for preventing selector switches from remaining in connection with operator appropriated link connectors that are in connection with other selector switches; operators' responsive devices at different operators' positions; and selecting mechanism for selecting operators' responsive devices that are free for selection, the link connectors performing their line joining function independently of said selecting mechanism that selects operators' responsive devices.

- 25 13. A telephone exchange system including telephone lines extending from stations to an exchange; link connectors at the exchange for extending calling lines; operator controlled switching apparatus for joining operator controlled link connectors with calling lines; additional link connectors; electro-magnetically operated selector switches for joining the additional link connectors with the aforesaid link connectors; operator controlled means for governing the operation of said selector switches; operator controlled electro-magnetically operated connector switches for connecting the selector switches that are connected with the operator appropriated link connectors, with desired lines; operators' responsive devices at different operators' positions; and selecting mechanism for selecting operators' responsive devices that are free for selection, the link connectors performing their line joining function independently of said selecting mechanism that selects operators' responsive devices.

- 30 14. A telephone exchange system including telephone lines extending from stations

- 5 appropriated link connectors that are in connection with other selector switches; operator controlled electro-magnetically operated connector switches for connecting the selector switches that are connected with operator appropriated link connectors, with desired lines; operators' responsive devices at different operators' positions; and selecting mechanism for selecting operators' responsive devices.
- 10 19. A telephone exchange system including telephone lines extending from stations to an exchange; link connectors at the exchange for extending calling lines; operator controlled switching apparatus for joining operator selected link connectors with calling lines; additional link connectors; electro-magnetically operated selector switches for joining the additional link connectors with the aforesaid link connectors; automatically operating operator controlled means for governing the extent of operation of said selector switches and causing them to become automatically connected with the first aforesaid link connectors when they are taken for use; and operator controlled electro-magnetically operated connector switches for connecting the selector switches that are connected with operator appropriated link connectors, with desired lines.
- 15 20. A telephone exchange system including telephone lines extending from stations to an exchange; link connectors at the exchange for extending calling lines; operator controlled switching apparatus for joining operator selected link connectors with calling lines; additional link connectors; electro-magnetically operated link selector switches for joining the additional link connectors with the aforesaid link connectors; means governed by said operator controlled switching apparatus and operating over operator selected link connectors for governing the extent of operation of said selector switches to cause them to remain in connection with operator selected link connectors; and operator controlled electro-magnetically operated connector switches for connecting the selector switches that are connected with operator appropriated link connectors, with desired lines.
- 20 21. A telephone exchange system including telephone lines extending from stations to an exchange; link connectors at the exchange for extending calling lines; operator controlled switching apparatus for joining operator controlled link connectors with calling lines; additional link connectors; electro-magnetically operated selector switches for joining the additional link connectors with the aforesaid link connectors;

operator controlled means for governing the extent of operation of said selector switches; means for preventing selector switches from remaining in connection with operator appropriated link connectors that are in connection with other selector switches; and operator controlled electro-magnetically operated connector switches for connecting the selector switches that are connected with operator appropriated link connectors, with desired lines.

22. A telephone exchange system including telephone lines extending from stations to an exchange; link connectors at the exchange for extending calling lines; operator controlled switching apparatus for joining operator selected link connectors with calling lines; additional link connectors; electro-magnetically operated selector switches for joining the additional link connectors with the aforesaid link connectors; automatically operating operator controlled means for governing the extent of operation of said selector switches and causing them to become automatically connected with the first aforesaid link connectors when they are taken for use; means for preventing selector switches from remaining in connection with operator appropriated link connectors that in connection with other selector switches; and operator controlled electro-magnetically operated connector switches for connecting the selector switches that are connected with operator appropriated link connectors, with desired lines.

23. A telephone exchange system including telephone lines extending from stations to an exchange; link connectors at the exchange for extending calling lines; operator controlled switching apparatus for joining operator selected link connectors with calling lines; additional link connectors; electro-magnetically operated link selector switches for joining the additional link connectors with the aforesaid link connectors; means governed by said operator controlled switching apparatus and operating over operator selected link connectors for governing the extent of operation of said selector switches to cause them to remain in connection with operator selected link connectors; means for preventing selector switches from remaining in connection with operator appropriated link connectors that are in connection with other selector switches; and operator controlled electro-magnetically operated connector switches for connecting the selector switches that are connected with operator appropriated link connectors, with desired lines.

24. A telephone exchange system including telephone lines extending from stations to an exchange; link connectors at the exchange for extending calling lines; operator controlled switching apparatus for joining

erators' positions; and selecting mechanism for selecting operators' responsive devices that are free for selection, the link connectors performing their line joining function 5 independently of said selecting mechanism that selects operators' responsive devices.

30. A telephone exchange system including telephone lines extending from stations to an exchange; link connectors at the exchange for extending calling lines; operator controlled switching apparatus for joining operator controlled link connectors with calling lines; additional link connectors; electro-magnetically operated selector switches 10 for joining the additional link connectors with the aforesaid link connectors; operator controlled means for governing the extent of automatic operation of said selector switches; operator controlled electro-magnetically operated connector switches 15 for joining the additional link connectors with the aforesaid link connectors; operator controlled means for governing the extent of automatic operation of said selector switches; operator controlled electro-magnetically operated connector switches 20 for connecting the selector switches that are connected with the operator appropriated link connectors, with desired lines; operators' responsive devices at different operators' positions; and selecting mechanism for selecting operators' responsive devices that are free for selection, the link connectors performing their line joining function independently of said selecting mechanism that selects operators' responsive devices. 25

31. A telephone exchange system including telephone lines extending from stations to an exchange; link connectors at the exchange for extending calling lines; operator controlled switching apparatus for joining operator selected link connectors with calling lines; additional link connectors; electro-magnetically operated selector switches 35 for joining the additional link connectors with the aforesaid link connectors; automatically operating operator controlled means for governing the extent of operation of said selector switches and causing them to become automatically connected 40 with the first aforesaid link connectors when they are taken for use; operator controlled electro-magnetically operated connector switches for connecting the selector switches that are connected with operator appropriated link connectors, with desired lines; operators' responsive devices at different operators' positions; and selecting mechanism for selecting operators' responsive devices that are free for selection, the link connectors 45 performing their line joining function independently of said selecting mechanism that selects operators' responsive devices. 50

32. A telephone exchange system including telephone lines extending from stations to an exchange; link connectors at the exchange for extending calling lines; operator controlled switching apparatus for joining operator selected link connectors with calling lines; additional link connectors; electro-magnetically operated link se- 55

lector switches for joining the additional link connectors with the aforesaid link connectors; means governed by said operator controlled switching apparatus and operating over operator selected link connectors 70 for governing the extent of operation of said selector switches to cause them to remain in connection with operator selected link connectors; operator controlled electro-magnetically operated connector switches 75 for connecting the selector switches that are connected with operator appropriated link connectors, with desired lines; operators' responsive devices at different operators' positions; and selecting mechanism for selecting operators' responsive devices that are free for selection, the link connectors performing their line joining function independently of said selecting mechanism that selects operators' responsive devices. 80

33. A telephone exchange system including telephone lines extending from stations to an exchange; link connectors at the exchange for extending calling lines; operator controlled switching apparatus for joining operator controlled link connectors with calling lines; additional link connectors; electro-magnetically operated selector switches for joining the additional link connectors with the aforesaid link connectors; operator controlled means for governing the extent of operation of said selector switches; means for preventing selector switches from remaining in connection with operator appropriated link connectors that are in connection with other selector switches; operator controlled electro-magnetically operated connector switches for connecting the selector switches that are connected with operator appropriated link connectors, with desired lines; operators' responsive devices at different operators' positions; and selecting mechanism for selecting operators' responsive devices that are free for selection, the link connectors performing their line joining function independently of said selecting mechanism that selects operators' responsive devices. 95

34. A telephone exchange system including telephone lines extending from stations to an exchange; link connectors at the exchange for extending calling lines; operator controlled switching apparatus for joining operator selected link connectors with calling lines; additional link connectors; electro-magnetically operated selected switches for joining the additional link connectors with the aforesaid link connectors; automatically operating operator controlled means for governing the extent of operation of said selector switches and causing them to become automatically connected with the first aforesaid link connectors when they are taken for use; means for preventing selector switches from remaining in connection with 110

- operator appropriated link connectors that are in connection with other selector switches; operator controlled electro-magnetically operated selector switches for connecting the selector switches that are connected with operator appropriated link connectors, with desired lines; operators' responsive devices at different operators' positions; and selecting mechanism for selecting operators' responsive devices that are free for selection, the link connectors performing their line joining function independently of said selecting mechanism that selects operators' responsive devices.
35. A telephone exchange system including telephone lines extending from stations to an exchange; link connectors at the exchange for extending calling lines; operator controlled switching apparatus for joining operator selected link connectors with calling lines; additional link connectors; electro-magnetically operated link selector switches for joining the additional link connectors with the aforesaid link connectors; means governed by said operator controlled switching apparatus and operat-
- ing over operator selected link connectors for governing the extent of operation of said selector switches to cause them to remain in connection with operator selected 30 link connectors; means for preventing selector switches from remaining in connection with operator appropriated link connectors that are in connection with other selector switches; operator controlled electro-magnetically operated connector switches for connecting the selector switches that are connected with operator appropriated link connectors, with desired lines; operators' responsive devices at different operators' positions; and selecting mechanism for selecting operators' responsive devices that are free for selection, the link connectors performing their line joining function independently of said selecting mechanism that 40 selects operators' responsive devices.
- 45
- In witness whereof, I hereunto subscribe my name this third day of July, A. D. 1912.
- MORTON L. JOHNSON.
